SLIDE FASTENER

Morris Garrison, Newark, N. J., assignor of one-half to Herman Blank, Newark, N. J.

Application February 23, 1940, Serial No. 320,347

6 Claims. (Cl. 24—205)

My invention relates to improvements in slide fasteners of the general type commonly called Zippers, and more particularly to slide fasteners for use on luggage.

5 In the various constructions of slide fasteners proposed heretofore, the locking elements have been attached directly to an edge of a strip of fabric, which strips are stitched to the complementary edges of a piece of luggage or travelling bag, for example. It is essential in the use of these prior constructions that the complementary edges carrying the Zipper be quite flexible or pliable in order that the locking elements can be moved into and out of locking position. Therefore, even though the characteristic of rigidity at these edges of the bag be desired to give added strength and to make the bag stand open better, this must be sacrificed if slide fasteners of the prior constructions are used.

10 20 With the foregoing in mind, it is one of the objects of my invention to provide an improved construction of slide fastener of the character referred to whereby the Zipper strips or units can be made entirely of metal, and can embody a rigid metal rail which in effect constitutes part of a rigid metal frame for the bag when my improved slide fastener or Zipper is assembled to the bag proper.

25 Another object of my invention is the provision of an improved construction of slide fastener of the character referred to which has advantages over those proposed heretofore in the way of durability and reliability of operation.

30 35 Other objects and advantages will hereinafter appear.

For the purpose of illustrating my invention, an embodiment thereof is shown in the drawings, in which

Figure 1 is an enlarged, fragmentary view, partly in section, of a slide fastener constructed and operating in accordance with my invention, the section being taken on the line 1—1 in Fig. 2, and the locking elements being shown in interlocking relation;

40 45 Fig. 2 is a sectional view, taken on the line 2—2 in Fig. 1;

Fig. 3 is a view similar to Fig. 1, showing the manner in which the locking elements are moved into and out of interlocking relation;

50 55 Fig. 4 is a fragmentary plan view of one of the parts after a step in its manufacture;

Figs. 5 and 5a are sectional views such as would be taken on the line 5—5 in Fig. 4, showing this part after further steps in its manufacture;

Fig. 6 is a sectional view of one of the locking elements, the section being taken on the line 6—6 in Fig. 7;

Fig. 7 is a top plan view of Fig. 6;

Fig. 8 is a bottom plan view of Fig. 6;

Fig. 9 is a top plan view of the slider element;

Fig. 10 is a bottom plan view of the slider element;

Fig. 11 is a section taken on the line 11—11 in Fig. 10;

Fig. 12 is a view looking upwardly in Fig. 9; and

Fig. 13 is a sectional elevational view, showing one of the operating positions of my improved fastener.

In the drawings, the reference numerals 10 and 11 designate two similar and complementary units comprising my improved slide fastener. Each unit comprises an L-shape, sheet-metal strip 13 provided with uniformly spaced slots 14 extending transversely thereof. A second sheet-metal strip 15 has its edge 16 secured to the edge 17 of the strip 13 by being folded over the latter, as shown more clearly in Fig. 2.

In making the strip 13, the slots 14 are first punched out as shown in Fig. 4, after which the edge 17 is bent up and the edge 18 folded over upon itself to form a bead or guiding edge, as shown in Fig. 5.

The locking elements 19 are of a conventional construction, and each is provided at one end thereof with a recess 20 and with a projection 21 opposite the recess, and at its other end with a hole 22 for receiving a flexible metallic element 23 in the form of a coil spring 23 with a fairly snug fit.

In assembling the parts, the locking elements 19 are placed in row formation, substantially uniformly spaced from each other a distance equal to that between the center-lines of any two adjacent slots 14 in the strip 13, by a spacing collar 19a which might be integral with the elements 19, and these elements are then inserted into the respective slots, as shown in Fig. 1. The coil spring is then inserted through the aligned holes 22 in the locking elements, to hold the latter in uniformly spaced relation with respect to each other. For the coil spring, it is proposed in some cases to use .075 inch steel wire, but other sizes might be found to be more desirable to meet particular requirements.

The edge portion 24 of the strip 15 is bent back upon itself as shown more clearly in Fig. 2, and is beaded over at 25. A reenforcing wire 26 is provided for bead 18.

When applied to a bag or other article, the units 10 and 11 are oppositely directed, as shown, with the secured edges 16 and 17 of the strips 13 and 15 adjacent each other.

5 A U-shape slider 28 bridges the L-shape strips 13, and has pivotally connected crosshead members 29, having a sliding fit on the beaded, guiding edges 18. The slider is provided on the cross-head members thereof with cam surfaces 29a disposed and arranged as shown in Fig. 10, so that the cam surfaces can engage the adjacent ends of the locking elements 19. The slider may be provided with a perforated ear 31 for attachment of a tab or bail 32 by which the slider may 10 be moved.

In the operation of my improved slide fastener, as the slider 28 is moved upwardly, as viewed in Fig. 3, the cam surfaces 29a engage the adjacent ends of about three or four of the 20 elements 19 to force them different distances outwardly. In this way, the coil spring 23 is flexed at these elements, to spread them out in a fan-like manner, as shown in Fig. 3, and permit movement of the elements 19 into interlocking 25 relation. As the slider passes on, the coil springs and the locking elements straighten out and become securely interlocked, as shown in Fig. 1, with the edges 16 engaging to form a seal. As the slider is moved downwardly, as viewed in Fig. 30 3, in the unlocking operation, a cam-like part 32a which the slider is provided at the longitudinal center-line thereof, becomes inserted between the spread-out elements 19 to separate the units 10 and 11.

35 A side 19b of the locking elements 19 is concave, to provide for the necessary clearance for the movement of these elements into and out of interlocking relation with respect to each other.

The clearances and the relative shapes and 40 dimensions of the various parts are made such as to cause the locking and unlocking action of the fastener to be smooth, and to give the required strength for any particular application.

It will be understood that various modifications within the conception of those skilled in the art, are possible without departing from the spirit of my invention or the scope of the claims.

I claim as my invention:

1. In a slide fastener, a relatively rigid metal 50 strip provided with uniformly spaced slots extending transversely thereof, locking elements disposed respectively in said slots for sliding movement relatively with respect to said strip into and out of locking position, and means common with respect to said elements for supporting the same for such movement.

2. In a slide fastener; two similar and complementary units each comprising an L-shape sheet-metal strip provided with uniformly spaced 60 slots extending transversely thereof, a second sheet-metal strip having an edge thereof secured to an edge of said L-shape strip, the other edge of said L-shape strip being beaded, locking elements disposed respectively in said slots and having a sliding fit therein and a sliding fit between said strips, and coil springs extending respectively through said elements and holding the same in assembled relation; said units being oppositely directed with said secured edges of said strips adjacent each other, and a slider bridging said L-shape strips and having a sliding fit on said beaded edges thereof, said slider being provided with cam surfaces for engaging the adjacent ends of said elements as the slider is moved in one direction whereby said springs are flexed to spread the engaged elements and advance them for movement into locking position, said slider being provided at the longitudinal center-line thereof with a cam-like part disposed for insertion between the spread-out elements to separate said units during the unlocking action as said slider is moved in the opposite direction.

are flexed to spread the engaged elements and advance them for movement into locking position, said slider being provided at the longitudinal center-line thereof with a cam-like part disposed for insertion between the spread-out elements to separate said units during the unlocking action as said slider is moved in the opposite direction. 5

3. In a slide fastener; two similar and complementary units each comprising an L-shape 10 sheet-metal strip provided with uniformly spaced slots extending transversely thereof, a second sheet-metal strip having an edge thereof secured to an edge of said L-shape strip, the other edge of said L-shape strip forming a guide edge, locking elements disposed respectively in said slots and having a sliding fit therein and a sliding fit between said strips, and a flexible metallic member extending through said elements and holding the same in assembled relation; said units 15 being oppositely directed with said secured edges of said strips adjacent each other, and a slider bridging said L-shape strips and having a sliding fit on said guiding edges thereof, said slider being provided with cam surfaces for engaging the adjacent ends of said elements as the slider is moved in one direction whereby said members are flexed to spread the engaged elements and advance them for movement into locking position, said slider being provided at the longitudinal 20 center-line thereof with a cam-like part disposed for insertion between the spread-out elements to separate said units during the unlocking action as said slider is moved in the opposite direction. 25

4. In a slide fastener; two similar and complementary units each comprising an L-shape sheet-metal strip provided with uniformly spaced slots extending transversely thereof, a second sheet-metal strip having an edge thereof secured to an edge of said L-shape strip, the other 40 edge of said L-shape strip forming a guide edge, locking elements disposed respectively in said slots and having a sliding fit therein and a sliding fit between said strips, and coil springs extending respectively through said elements and holding the same in assembled relation; said units being oppositely directed with said secured edges of said strips adjacent each other, and a slider bridging said L-shape strips and having a sliding fit on said guiding edges thereof, said slider being provided with cam surfaces for engaging the adjacent ends of said elements as the slider is moved in one direction whereby said springs are flexed to spread the engaged elements and advance them for movement into locking position, said slider being provided at the longitudinal center-line thereof with a cam-like part disposed for insertion between the spread-out elements to separate said units during the unlocking action as said slider is moved in the opposite direction. 45

5. In a slide fastener; two similar and complementary units each comprising an L-shape sheet-metal strip provided with uniformly spaced slots extending transversely thereof, a second 65 sheet-metal strip having an edge thereof secured to an edge of said L-shape strip, the other edge of said L-shape strip being beaded, locking elements disposed respectively in said slots, and having a sliding fit therein and a sliding fit between said strips, and flexible metallic members extending respectively through said elements and holding the same in assembled relation; said units being oppositely directed with said secured edges of said strips adjacent each other, and a 70

75

slider bridging said L-shape strips and having a sliding fit on said beaded edges thereof, said slider being provided with cam surfaces for engaging the adjacent ends of said elements as the slider 5 is moved in one direction whereby said members are flexed to spread the engaged elements and advance them for movement into locking position, said slider being provided at the longitudinal center-line thereof with a cam-like part 10 disposed for insertion between the spread-out elements to separate said units during the unlocking action as said slider is moved in the opposite direction.

6. In a slide fastener, a relatively rigid metal strip provided with uniformly spaced slots extending transversely thereof, locking elements disposed respectively in said slots for sliding movement relatively with respect to said strip 5 into and out of locking position, a side of each of said locking elements being concave, and means common with respect to said elements for supporting the same for such movement.

10

MORRIS GARRISON.
